US00D793773S

(12) United States Design Patent (10) Patent No.: US D793,773 S
(45) Date of Patent: * Aug. 8, 2017

(54) NIGHTSTAND

(71) Applicant: Jack Schmitt, Mission Viejo, CA (US)

(72) Inventor: Jack Schmitt, Mission Viejo, CA (US)

(73) Assignee: Amini Innovation Corporation, Pico Rivera, CA (US)

() Term: 15 Years

(21) Appl. No.: 29/563,428

(22) Filed: May 4, 2016

(51) LOC (10) Cl. 06-04

(52) U.S. Cl.

USPC D6/668

(58) Field of Classification Search
